UNITED STATES PATENT OFFICE.

ANDRÉ FÉLIX JACQUEMIN, OF SAUCOURT, FRANCE.

FURNACE FOR THE HEATING AND UNWINDING OF WIRE.

Application filed March 26, 1925. Serial No. 18,574.

To all whom it may concern:

Be it known that I, ANDRÉ FÉLIX JACQUEMIN, citizen of the Republic of France, residing at Saucourt, Haute-Marne, France, have invented certain new and useful Improvements in Furnaces for the Heating and Unwinding of Wire, of which the following is a specification.

My invention relates to a furnace adapted for the heating of iron wire or the like in the state of rolls, and for the unwinding of the same without cooling the wire to any appreciable degree.

The said furnace comprises a chamber in which is mounted upon a pivot a device resembling a rotating drum or reel which is adapted to carry the roll of wire and whereof the central part constitutes the heating portion of the furnace. This latter has a lateral aperture for the discharge of the wire in the highly heated state in order to supply the machines utilizing the wire according as the latter is unwound from the said drum or reel.

Various particular arrangements may be optionally provided in order to facilitate the operating of the furnace and in order to improve its working, as will be set forth in the following description relative to an embodiment of the invention.

In the appended drawings:

Fig. 1 is an elevational section of the said furnace.

Fig. 2 is a sectional and plan view, according to the line II—II of Fig. 1.

In the said figures, the furnace properly so called comprises a chamber 3 which is lined with refractory material and is mounted on the upper part of a metallic frame 5; said chamber is closed by a cover 6 and contains a drum or reel of a refractory metal 7 which is disposed upon a disk 8 mounted at the end of the hollow shaft 9 which is supported at the bottom upon a ball bearing 10 secured to the main frame.

The central circular part of the drum 7 constitutes the heating portion of the said furnace, and comprises to this effect a grate 11. Upon the periphery of the said drum is provided an annular flange or support 12 supporting the roll of wire 13 to be heated. Suitable apertures 14 are provided around the chamber 3 for the discharge of the products of combustion, and in the interior of

the furnace an annular wall 15 is disposed above the said apertures, forming a baffle. Between the bottom 16 of the chamber 3 and the disk 8 is provided a hydraulic joint 17 supplied with water by a special conduit 18. The chamber 3 comprises an aperture 19 communicating with a channel 20 for the discharge of the wire. I may further provide a sight hole 21 closed by a sliding door 22 for the periodical observation of the functioning.

In the disk 8 are formed apertures 22 for the passage of the air for the combustion which is admitted below the grate 11 and enters the furnace through the door 23. In its central region the disk 8 forms a basin 24 communicating at the bottom with a conduit 25 formed at the centre of the vertical shaft 9, said conduit being connected through the stuffing box 26 with a water pipe 27. To the shaft 9 is keyed the bevel gear 28 co-operating with a like gear 29 mounted upon a rod 30 which is slidable lengthwise in the bearings 31, 32 of the main frame and has at the end a hand wheel 33.

The operation of the said furnace is as follows:

The cover 6 of the furnace is removed, and a roll of wire 13 is placed upon the drum 7 and is laid upon the flanged part 12. Fuel is disposed in the grate 11 and lighted, and the said cover is then put in place; air is admitted through the aperture 23 while a certain quantity of water which is delivered through the conduit 25 and fills the basin 24 wherein it evaporates. The mixture of air and water which enters the heating portion through the grate 11 will further the combustion and produces flames which impinge upon the roll of wire 13, passing between the flanged part 12 and the baffle 15 and issuing from the furnace through the apertures 14.

In this manner the said roll of wire becomes rapidly heated, and its temperature may be readily observed by opening the door 21 and examining the said roll while turning the hand wheel 33 in order to rotate the hollow shaft 9 and the drum 7.

When it is considered that the wire has been brought to a sufficient temperature, it is seized by the outer end and drawn through the aperture 19; it is simply necessary to bring this end of the wire to the machines

utilizing the same which may be mounted as close to furnace as desired, and which may be supplied in a continuous manner as the wire is unwound from the drum 7. It is 5 obvious that during its unwinding, the wire will not be cooled to any appreciable degree, and it may thus be treated in the most favourable conditions of temperature.

10 The furnace according to my said invention is adapted for use in a considerable number of industries. For example it provides for the continuous feeding of bolt making machines; in the known methods, such machines are periodically supplied 15 with short lengths of wire which become rapidly cooled and are difficult to handle.

20 The annealing furnace provides for the utilization of the waste wire from the rolling mills. Hot rolling can always be employed with a reduced number of operations for small section iron bars, mouldings, and especially thin hoop iron (0.5 mm.) which could not be rolled hot by the known methods; such products were treated in the

cold state and had to be put frequently 25 through the rolls, with frequent annealing in the meantime.

The utilization of the furnace according to my said invention is not limited to the above-mentioned examples, and the said furnace is adapted for a wide range of uses. The furnace itself is susceptible of all suitable modifications in detail according to each particular case, without departing 30 from the principle of the invention. 35

I claim:

A furnace for heating wires, comprising a chamber in which a sort of revoluble drum-like element is mounted upon a pivot; said drum-like element carries the wire, and its 40 central part constitutes the heating portion of the furnace, a lateral aperture being provided in the said chamber for the discharge of the wire as it is unrolled from the drum-like element. 45

In testimony whereof I have hereunto set my hand.

ANDRÉ FÉLIX JACQUEMIN.
